MILUS M. HOUSE, OF KANSAS CITY, MISSOURI.

OCCLUSAL GRINDING DEVICE FOR ARTICULATORS.

Application filed November 16, 1925. Serial No. 69,374.

The present invention relates to dental appliances, and aims to provide a novel and efficient form of occlusal grinding device for use with articulating apparatus, such as is employed in the making of artificial dentures or like work. The principal object in view is to provide a mechanism which may be applied to articulators for the purpose of performing such a grinding operation as will eliminate the locked relation which commonly exists between sets of artificial teeth, my improved grinding operation resulting in a horizontal freedom of movement of the dentures in the various positions of occlusion which they may assume.

For the purpose of performing this function, I have devised a grinding device adapted to be applied to the various forms of articulators now in common use, the operation of this grinding mechanism being adapted to impart a movement of translation to one of the dentures, the direction of which movement is in a limited circular path, of a nature adapted to produce a grinding effect simulating that which is due to the ordinary wear of natural teeth in the normal use of the same.

As actually embodied in practice, I have devised a grinding mechanism adapted to be removably attached to the articulator, and including a movable plate having means of attachment to the upper denture, and provided with a pair of eccentrics operated in unison to effect the desired movement of the movable plate in the operation of grinding. A common drive member, designed to be operated by belt power, is arranged for driving the eccentric elements in unison, with the axes of the eccentric elements so located as to result in a grinding movement of the plate having its forward limit of movement corresponding to the position of normal central occlusion of the dentures.

It is further sought to provide a device of the character described in which provision is made for initially adjusting the position of the movable plate so that it will be symmetrically arranged with reference to what is known as the sagittal plane.

With the foregoing principal objects in view, as well as various minor objects which will appear in the course of the detailed description, the invention will now be described by reference to the accompanying drawings illustrating one form of construc-

tion which I have devised for embodying the proposed improved mechanism, after which those features and combinations deemed to be novel will be particularly set forth and claimed.

60

In the drawings—

Figure 1 is a side elevation, illustrating an articulator having an occlusal grinding device constructed in accordance with the present invention;

65

Figure 2 is a plan view of the same;

Figure 3 is a central vertical section, taken on the line III—III of Figure 2, the denture models being omitted;

65

Figure 4 is a horizontal section, taken on the line IV—IV of Figure 1; and

Figure 5 is a detail section, taken on the line V—V of Figure 2.

Referring now to the drawings in detail, these illustrate the improved occlusal grinder in its operative relation to a common and well known form of articulator now in commercial use, this articulator comprising a lower supporting frame 7 and an upper frame member 8 which is movably supported upon the lower frame 7 for pivotal sliding movement by means of what are known as rotation points 9, 10, engaging suitably curved or inclined surfaces, as required for accommodating the movement of the upper frame member 8 in accordance with the different occlusal positions assumed by the upper denture 11 with reference to the lower denture 12 (see Figure 1). The middle portion of the upper frame member 8 is engaged by a spring element 14 secured centrally to the upper portion of the lower frame member 7, said spring acting to maintain the dentures in yielding engagement in all positions of the grinding operation.

70

To the lower frame member 7 is detachably secured, as by means of the clamping screws 15, the usual denture model support 16 having its forward end provided with the inclined surface 17 for engagement with the lower end of the usual incisor guide pin 18 carrying the incisor guide element 19, the upper end of the pin 18 being designed to be clamped to the forward end of the usual upper model support which is attached to the upper frame 8, said upper model support, however, not being illustrated in the drawings, but being displaced by the grinding device forming the subject of the present application.

80

100

105

110

The improved grinding device herein illustrated is designed to be mounted in lieu of the upper denture model support in any of the common forms of articulators, the connection in the present construction to the upper articulator frame 8 being made by means of the attaching screws 21 already present for the attachment of the upper model supporting arm, these screws 21 operating to secure the rear end of the fixed grinder plate 22, the forward end of which is provided with a passage 23 for the upper end of the incisor pin 18, which is held in position by means of a clamping screw 24.

To the under face of the plate 22 is applied the movable grinder plate 25 which is provided with retaining screws 26 for holding the plaster cast 27 that supports the upper denture model 11. The plate 25 is supported by means of a set of screws 28, the lower ends of which are supplied with nuts 29 engaging the under face of the plate 25; openings 30 are provided in the plate 22 of sufficient size to accommodate the movements of the screws 28 corresponding to the movement of the plate 25, the heads of said screws 28 being engaged by washers 31 supported by the margins of the openings 30, as clearly shown in Figure 5.

At opposite sides of the center of the plate 25, the same is provided with a pair of vertical stub shafts 32 for the mounting of gear wheels 33 formed with eccentric hub portions 34 mounted in openings 35 formed in the plate 22; the upper margins of these openings 35 are flanged, as shown at 36 in Figure 5, the height of the flanges 36 being sufficient to support the eccentric portions 35 of the gears 33 out of engagement with the upper face of the plate 25. In line with the shafts 32, the plate 22 is provided with a third vertical stub shaft 38 for journaling a belt pulley 39, to the lower hub portion of which is secured a drive gear 40 in mesh with both of the gears 33, a suitable belt drive (not shown) being designed to be applied to the pulley 39 for thus operating both of the gear elements 33 in unison and in the same direction, and thus correspondingly operating the eccentric elements 34 for actuating the plate 25 and the denture model 11 supported thereby.

Adjacent to the front and rear margins of the plate 25, the same is provided with the screws 45 projecting upward through openings 46 of a size sufficient to receive the lock nuts 47 mounted on the screws 45, when said nuts are turned down upon said screws 45. The screws 45 are in line with the shaft 38 which is positioned centrally of the plate 22, so that the function of the nuts 47 is, by being clamped down within the openings 46, to initially position the plate 25 with its middle longitudinal line coinciding with what is known as the sagittal plane of the denture

models 11 and 12. After this initial adjustment, the nuts 47 are turned up upon the screws 45, to thus release the plate 25 to the action of the eccentrics 34 in carrying out the grinding operation.

In the operation of the improved grinder, after the upper model supporting arm has been removed from the upper frame member 8, the grinder device is secured in position by means of the screws 21, and the device is now adjusted so as to position the plate 25 centrally with reference to the sagittal plane, as above explained, the nuts 47 being lowered upon the screws 45 into the openings 46 for this purpose; in this adjustment, care is also taken to have the eccentric elements 34 in forward position, that is pointing toward the front of the appliance, as represented in Figure 4. This location of the eccentric elements is obtained by rotating the pulley 39 until the openings 50 in the pinion or gears 33 (see Figure 2), which thus serve both as oil and guide openings, are in front of the shafts 32, which position corresponds to the proper starting points of movement for these eccentric elements.

After the mounting of both models in position, the nuts 47 are raised into clamping engagement with the heads of the screws 45, and power is applied by means of the belt attached to the pulley 39. The grinding operation is carried out first for the position of central occlusion, the joint operation of the two eccentric elements 34, as driven from the common gear element 40, resulting in a limited movement of translation of the plate 25 and its upper denture model 11, which movement is thus confined to a circular path of short radius. The term "translation", as herein used, has the meaning as employed in dynamics to refer to motion in which all the parts of the moving body follow the same direction, i. e. motion without rotation. This obviously is the desired type of movement to produce the character of grinding effect desired, namely, that corresponding to a mortar and pestle action, most nearly simulating the wear produced by the set of natural teeth in their normal use in mastication. Since the eccentric elements operate in unison at opposite sides of the central shaft 38, it is apparent, therefore, that the grinding operation is carried out symmetrically upon opposite sides of the sagittal plane, thus resulting in a uniform grinding or triturating function throughout. Moreover, since the forward limit of movement of the eccentric elements 34, as illustrated in Figure 4, at the beginning of each grinding movement, and this corresponds to the position of normal central occlusion, each grinding movement is effected by a movement of the plate 25 from its rear position toward the front and back to its rear or starting position again.

After grinding for the position for central occlusion, the articulator is adjusted to position the teeth for what is known as "end to end" biting relation, and the operation of 5 grinding is carried out for this position, moving the articulator from time to time until central occlusion is reached. After this, the grinding process is carried out for 10 right and left lateral occlusion, each time proceeding back to the position of central 15 occlusion; and following this the same process is carried out for both positions of right and left lateral occlusion from protrusive occlusion, and back to the position of central 20 occlusion.

From the foregoing it will be seen that I have provided a practical and efficient device 25 for carrying out all of the desired objects of the invention, and while I have illustrated what I now regard as the preferred form of 30 embodiment of the improvements, I desire to reserve the right to make all such changes and modifications as may fairly fall within the scope of the appended claims.

25 What I claim is:

1. An occlusal grinding device comprising the combination of means for holding a pair of dentures in occluded relation, and means for imparting a translational movement of small amplitude to one of said dentures and confining said movement to a circular path.

2. An occlusal grinding device for articulators comprising a plate provided with means for detachably connecting the plate to the frame of the articulator, a movable denture supporting plate carried by said first plate, and means for imparting a translational movement of small amplitude to said 35 movable plate and confining said movement to a circular path.

3. An occlusal grinding device for articulators comprising a plate provided with means for detachably connecting the plate to the frame of the articulator, a movable denture supporting plate carried by said first plate, means for imparting to said supporting plate a translational movement of small 45 amplitude in a circular path, and an incisor guide pin connected with the front of said first plate.

4. An occlusal grinding device for articulators comprising a plate provided with means for detachably connecting the plate to the frame of the articulator, a movable denture supporting plate carried by said first plate, means for adjusting and initially setting said movable plate into symmetrical 55 relation to the sagittal plane and means for imparting to said movable plate a translational movement in a circular path of small radius.

5. An occlusal grinding device for articulators, comprising a plate adapted to be secured to the articulator frame, a movable

denture supporting plate carried by said first plate, means comprising a pair of eccentric elements for imparting to said movable plate a translational movement of small amplitude in a circular direction, and means 70 for rotating said eccentrics together in unison.

6. An occlusal grinding device for articulators, comprising a plate adapted to be secured to the articulator frame, a movable 75 denture supporting plate carried by said first plate, means for imparting a grinding movement to the movable plate comprising a pair of eccentric elements, and gear connections for actuating said eccentric elements 80 together in unison and including means whereby said eccentric elements may be set to start the initial movement thereof in the forward position of said elements corresponding to the normal position of central 85 occlusion of the articulator.

7. An occlusal grinding device for articulators, comprising a plate adapted to be secured to the articulator frame, a movable denture supporting plate carried by said first 90 plate, means for adjusting and initially setting said movable plate into symmetrical relation to the sagittal plane while said plate is in the position corresponding to the normal position of central occlusion, means for imparting a grinding movement to the movable plate comprising a pair of eccentric elements with the forward limit of movement of the eccentrics corresponding to the normal position of central occlusion 95 100 of the denture, and gear connections for actuating said eccentric elements together in unison.

8. A dental grinding process which consists in holding a pair of artificial dentures in occluded relation, and producing a translational movement of small amplitude of one of said dentures while positively confining said movement to a continuous substantially 105 circular path.

9. In a dental appliance, the combination of means for holding a pair of dentures in occluded relation, and means for imparting a continuous unidirectional movement of small amplitude to one of said dentures for effecting a triturative action along the points of contact of the dentures.

10. A dental appliance comprising a denture-holding member, a second denture-holding member movable relative to said first member, a denture carried by each of said members, and means for imparting a continuous unidirectional movement of small amplitude to one of said dentures for effecting a milling action between dentures.

11. A dental appliance comprising a denture-holding member, a second denture-holding member movable relative to said first member, a denture carried by each of said members, means for adjusting said members 115 120 125 130

4
into different positions of occluded relation of the dentures, and means for imparting a continuous unidirectional movement of small amplitude to one of said dentures for effecting a triturative action between the dentures.

12. In a dental appliance, the combination of means for holding a pair of dentures in occluded relation, and means for imparting a continuous unidirectional movement of small amplitude to one of said dentures in a direction substantially coinciding with the occlusal plane and about an axis at right angles to said plane.

13. In a dental appliance, the combination of means for holding a pair of dentures in occluded relation, and means for imparting a continuous unidirectional movement of small amplitude to one of said dentures in a

direction substantially coinciding with the occlusal plane and about an axis at right angles to said plane and falling within the boundary of the lingual portions of the dentures.

14. A dental appliance comprising a pair of dentures, an articulator frame comprising relatively adjustable sections carrying said dentures and operative to maintain the same in occluded relation, and means operating independently of any relative movement between said frame sections for imparting a continuous unidirectional movement of small amplitude to one of said dentures.

In witness whereof I hereunto affix my signature.

MILUS M. HOUSE.
